Primary Examiner — Patricia A Palasik*(74) Attorney, Agent, or Firm* — Edell, Shapiro & Finn, LLC(57) **CLAIM**

The ornamental design for a welding/cutting enclosure panel, as shown and described.

DESCRIPTION

FIG. 1 is a rear perspective view of a panel for a welding/cutting enclosure according to the present invention;

FIG. 2 is a front perspective view of the panel for a welding/cutting enclosure of FIG. 1;

FIG. 3 is a rear view of the panel for a welding/cutting enclosure of FIG. 1;

FIG. 4 is a front view of the panel for a welding/cutting enclosure of FIG. 1;

FIG. 5 is a left side view of the panel for a welding/cutting enclosure of FIG. 1;

FIG. 6 is a right side view of the panel for a welding/cutting enclosure of FIG. 1;

FIG. 7 is a top view of the panel for a welding/cutting enclosure of FIG. 1; and,

FIG. 8 is a bottom view of the panel for a welding/cutting enclosure of FIG. 1.

Any portions shown using dashed lines are part of the welding/cutting enclosure panel and form no part of the claimed design.

1 Claim, 6 Drawing Sheets(56)
